GROVER C. DAVIS, OF NEW YORK, N. Y.

SPARK-PLUG.

1,031,626.

Specification of Letters Patent.

Patented July 2, 1912.

Application filed March 10, 1911. Serial No. 613,620.

To all whom it may concern:

Be it known that I, GROVER C. DAVIS, a citizen of the United States, and a resident of New York, borough of Brooklyn, county of Kings, and State of New York, have invented certain new and useful Improvements in Spark-Plugs, of which the following is a full, clear, and exact specification.

This invention relates to a class of devices 10 or spark plugs adapted for use in conjunction with the operation of combustion engines.

My invention has for its object primarily to provide a form of spark plug designed 15 for use in connection with the compression chamber of a combustion engine for exploding the charges of gaseous fuel admitted thereto and which may be conveniently adjusted without removal from the engine for 20 changing the electric contact points so as to effectively clear the contact points of all deposits of non-conducting electric products which may accumulate thereon during 25 the operation of the combustion engine; and to provide a spark plug also adapted to be adjusted without removal from the engine for replenishing with a new contact point one which may be rendered useless by being damaged or burned-out, thus obviating 30 the waste of time and difficulty resulting from the methods in ordinary use. These advantages are attained mainly by providing a casing in which is rotatably held an insulated transmitting wire carrying upon 35 one end thereof a plurality of sparking points which are adapted to be moved successively so as to provide a spark gap between each of said sparking points and a sparking point provided upon the casing so 40 that in event of oil, carbonaceous substances, dust, or the like becoming deposited thereon the sparking point of the transmitting wire in register with the sparking point of the casing may be replaced with another point 45 by revolving said transmitting wire.

Another object of the invention is to provide a device or means adapted to manually rotate the insulated transmitting wire to predetermined positions whereby a positive 50 register of the sparking points thereof with the sparking point of the casing will be insured at all times; and a further object of the invention is to provide a spark plug of compact form and a simplified arrangement 55 of parts which may be readily assembled and made very durable.

With these and other objects in view, the invention will be hereinafter more particularly described with reference to the accompanying drawing, which forms a part of 60 this specification, and will then be pointed out in the claims at the end of the description.

In the drawing, Figure 1 is an elevation of one form of spark plug embodying my invention. Fig. 2 is a top plan, partly in section, of the spark plug. Fig. 3 is an inverted plan of the bottom of the spark plug, and Fig. 4 is a section taken on the line II—II of Fig. 1.

The spark plug 10 has a tubular casing 11 having its lower end exteriorly threaded, at 12, so as to be screwed in a threaded opening of any suitable part of the wall of the compression chamber of a combustion engine. The end of the tubular casing 11 opposite to the threaded end 12 thereof is circumferentially cut-out or reduced, as at 13, in order to provide an annular shoulder 14. Interiorly of the threaded end 12 of said 20 tubular casing is an annular band or flange 14^a, and upon the under surface of the threaded end is a projecting sparking point 15. Through the tubular casing 11 is disposed a transmitting wire 16 which is embedded in 25 an insulating post 17 extending some distance above the tubular casing, and said transmitting wire is of greater length than the insulating post so as to extend beyond both ends thereof, as shown.

Upon the end of the transmitting wire 16 extending beyond the end of the insulating post 17 at the threaded end of the tubular casing 11 is provided a plurality of sparking points, as 18. I prefer to employ six 30 of the sparking points 18 and arrange said points in the shape of a six-arm star so that every two sparking points thereof will be disposed diametrically opposite to each other. The opposite end of the transmitting 35 wire 16 is threaded, as at 19, and upon said threaded end is a cap or binding post 20 to which is held an arm 21 having a clip 22 provided upon the opposite end thereof. The clip 22 is adapted to connect the arm 19 40 to the wire leading from one pole of the usual or any preferred type of storage battery while the wire leading from the other pole of the storage battery may be connected 45 in any suitable manner so as to provide an 45 electric circuit through the clip 22, over the arm 21, through the transmitting wire 16.

and through one of the sparking points 18. At the same time the current of electricity will pass from the other pole of the storage battery through the tubular casing 11 to the sparking point 15 thereof.

5 About midway of the insulating post 17 is a projecting annular flange 23 against which rests one edge of a jacket 24 which extends around said insulating post to the end of the threaded end of the tubular casing 11 and terminates with an exterior annular band or flange 25 which abuts against the annular band or flange 14^a interiorly of said tubular casing. By forming the jacket 24 and the tubular casing 11, as described and illustrated, a concentric recess 26 is provided between the inner surface of said casing and the outer surface of the jacket. The end of the jacket 24 opposite to the annular flange 25 is exteriorly threaded, as at 27, and upon said threaded end of the jacket is held the annular ring or flange 28 of the ratchet 29 of a device 30 which is adapted to rotate the jacket 24 and simultaneously therewith revolve the insulating post 17 for rotating the transmitting wire 16 so as to adjust the sparking points 18 whereby one of said sparking points when moved will clear the sparking point 15 of the tubular casing 11 of all deposit thereon of oil or other foreign substances which may tend to prevent proper generating of sparks between said points.

The ratchet 29 of the adjusting device or means 30 is circular in form and proportionately larger in diameter than the circumference of the sparking points 18, and in the peripheral edge of the ratchet 29 is formed a plurality of notches 31 which are 40 of equal number to the sparking points 18 and are spaced apart at intervals so that when revolved the transmitting wire 16 will be rotated to move one of the sparking points 18 in register with the sparking point 15 of the tubular casing 11. In order to 45 manually rotate the ratchet 29 I provide upon the insulating post 17 and underneath the ratchet 29 a movable plate 32 which has a projecting part 33, and upon one surface 50 of said projecting part is pivoted a lever 34. The lever 34 has a handle 35 by which said lever may be manually moved, and projecting from one edge of the pivoted end thereof is a toe 36. In proximity to the opposite 55 edge of the pivoted end of the lever 34 is pivotally held upon the projecting part 33 of the movable plate 32 a dog 37 which is adapted to engage one of the notches 31 of the ratchet 29, and to said dog is held one 60 end of a spring 38 which has its other end engaging the edge of the pivoted end of the lever 34 so as to normally serve to hold the dog in contact with the ratchet 29. Between the movable plate 32 and the annular shoulder 65 14 of the tubular casing 11 is rigidly

held a plate 39 which may be secured in any suitable manner, for instance by a screw, as 40. In the path of movement of the toe 36 of the lever 34 and at one edge of the rigidly held plate 39 is pivoted one end of an arm 41 of a pawl 42. Projecting substantially 70 at a right angle from one edge of the arm 41 or the pawl 42 is a tooth 43 which is adapted to engage one of the notches 31 of the ratchet 29 so as to prevent said ratchet from movement when in engagement therewith, and upon the end of the arm 41 opposite to its pivoted end is a finger 44 one edge of which is adapted to be engaged by the toe 36 of the lever 34 so as to swing the pawl 42 in a direction, as indicated by dotted lines at 45, for freeing the engagement of the tooth 43 from one of the notches 31 of the ratchet 29 when said lever is moved in a direction, as shown by dotted lines at 46. 80 To the pawl 42 is held one end of a spring 47 the other end of which is fastened upon the rigidly held plate 39 and said spring serves to force the pawl 42 so that the tooth 43 thereof will normally engage one of the 85 notches 31 of the ratchet 29. Encircling the jacket 24 of the insulating post 17 and within the concentric recess 26 is arranged a spiral spring 48 normally serving to prevent the inner jacket 24 and the insulating 90 post 17 from being forced from the tubular casing 11 by the suction created in the compression chamber of a combustion engine by the alternate movement of the piston there- 95 of. As illustrated, when the lever 34 is 100 moved to the position, as shown by the dotted lines 46, the toe 36 thereof will guide the finger 44 of the pawl 42 so as to release the engagement of the tooth 43 with one of the notches 31 of the ratchet 29. The plate 105 32 will thereby be moved and simultaneously therewith the dog 37 will force the ratchet to rotate the insulating post 17 for revolving the transmitting wire 16 at which time 110 one of the sparking points 18 will be positioned so as to register with the sparking point 15 of the tubular casing 11 for continuously generating electric sparks between said points.

In the foregoing description I have embodied the preferred form of my invention, but I do not wish to be understood as limiting myself thereto, as I am aware that modifications may be made therein without departing from the principle or sacrificing any 115 of the advantages of this invention; therefore I reserve to myself the right to make such changes as fairly fall within the scope thereof.

Having thus described my invention, I 125 claim as new and desire to secure by Letters Patent:

1. In a spark plug; the combination with a tubular casing having one end thereof 130 exteriorly threaded and having its opposite

end exteriorly reduced, said tubular casing having an annular band formed interiorly of its threaded end and having a sparking point projecting from the underside of its 5 threaded end; of an inner jacket rotatable within the tubular casing and abutting against the annular band of said casing; an insulating post held within the jacket and rotatable therewith, said post projecting beyond one end thereof; a transmitting wire 10 embedded in the insulating post, said transmitting wire being of greater length than the insulating post so as to extend beyond the ends of said insulating post; a plurality 15 of sparking points provided upon the end of the transmitting wire at the threaded end of the tubular casing; means provided upon the opposite end of the transmitting wire and adapted to connect said wire to a storage battery; and a device provided upon the tubular casing and adapted when moved to rotate the jacket for revolving the transmitting wire so as to register one of the 20 sparking points of the transmitting wire 25 with the sparking point of said tubular casing.

2. In a spark plug; the combination with a tubular casing having one end thereof exteriorly threaded and having its opposite 30 end exteriorly reduced; an annular band formed interiorly of the threaded end of the tubular casing; a sparking point projecting from the underside of said threaded end; of an inner jacket rotatable within the 35 tubular casing and having an annular band formed exteriorly at one end thereof whereby a concentric recess is provided between said inner jacket and the interior surface of the tubular casing; an insulating post held within the jacket and projecting beyond one end thereof; a transmitting wire 40 embedded in the insulating post; said transmitting wire being of greater length than the insulating post so as to extend beyond the ends of said insulating post; a plurality 45 of sparking points provided upon the end of the transmitting wire at the threaded end of the tubular casing; means provided upon the opposite end of the transmitting wire 50 and adapted to connect said wire to a storage battery; a device provided upon the tubular casing and adapted when moved to rotate the insulating post for revolving the transmitting wire so as to register one of the 55 sparking points of the transmitting wire with the sparking point of said tubular casing; and a spiral spring encircling the jacket of the insulating post and normally serving to retain said jacket and the insulating post 60 within the tubular casing against displacement by the suction created by the piston of a combustion engine.

3. In a spark plug; the combination with a tubular casing having one end thereof exteriorly threaded and having its opposite

end exteriorly reduced, said tubular casing having an annular band formed interiorly of its threaded end and having a sparking point projecting from the underside of its threaded end; of an inner jacket rotatable within the tubular casing and having an annular band formed exteriorly at one end thereof and abutting against the annular band of the tubular casing whereby a concentric recess is provided between said inner jacket and the interior surface of the tubular casing; an insulating post held within the tubular casing and projecting beyond one end thereof; a transmitting wire 70 embedded in the insulating post, said transmitting wire being of greater length than the insulating post so as to extend beyond the ends of said insulating post; a plurality 75 of sparking points provided upon the end of the transmitting wire at the threaded end of the tubular casing; means provided upon the opposite end of the transmitting wire and adapted to connect said wire to a storage battery; a ratchet provided upon the insulating post and having an annular flange connected to said inner jacket; a 80 movable plate provided upon the insulating post between the ratchet and the rigidly held plate of the tubular casing; means provided upon the movable plate and adapted 85 when moved to rotate the ratchet and the insulating post for revolving the transmitting wire so as to register one of the sparking points of the transmitting wire with the 90 sparking point of said tubular casing; and a spiral spring encircling the jacket of the insulating post and normally serving to retain said jacket and the insulating post within the tubular casing against displacement by the suction created by the piston 95 of a combustion engine.

4. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projecting from the underside of its threaded end; of an inner jacket rotatable 110 within the tubular casing and having an annular band formed exteriorly at one end thereof and abutting against the annular band of the tubular casing whereby a concentric recess is provided between said inner jacket and the interior surface of the tubular casing; an insulating post held within the tubular casing and projecting beyond one end thereof; a transmitting wire embedded 115 in the insulating post, said transmitting wire being of greater length than the insulating post so as to extend beyond the ends of said insulating post; a plurality of sparking points provided upon the end of the transmitting wire at the threaded end of the 120

transmitting wire at the threaded end of the 130

- 4
- tubular casing; means provided upon the opposite end of the transmitting wire and adapted to connect said wire to a storage battery; a plate rigidly held upon the reduced end of the tubular casing; a ratchet provided upon the insulating post and having an annular flange upon one surface thereof, said annular flange being connected to the inner jacket; a movable plate provided upon the insulating post between the ratchet and the rigidly held plate of the tubular casing; a dog pivoted upon the movable plate and adapted to engage the ratchet; a pawl pivotally held upon the rigidly held plate and adapted to also engage the ratchet; means provided upon the movable plate and adapted when moved to swing said pawl from engagement with the ratchet whereby said ratchet will be moved to rotate the insulating post for revolving the transmitting wire so as to register one of the 50 sparking points of the transmitting wire with the sparking point of said tubular casing; and a spiral spring encircling the jacket of the insulating post and normally serving to retain said jacket and the insulating post within the tubular casing against 55 displacement by suction created by the piston of a combustion engine.
5. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projecting from the underside of its threaded end; of an inner jacket rotatable within the tubular casing and having an annular band formed exteriorly at one end thereof and abutting against the annular band of the tubular casing whereby a concentric recess is provided between said inner jacket and the interior surface of the tubular casing; 60 an insulating post held within the tubular casing and projecting beyond one end thereof; a transmitting wire embedded in the insulating post, said transmitting wire being of greater length than the insulating post so as to extend beyond the ends of said insulating post; a plurality of sparking points provided upon the end of the transmitting wire at the threaded end of the tubular casing; means provided upon the opposite end of the transmitting wire and adapted to connect said wire to a storage battery; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to engage one of the notches of the ratchet; a spring having one end held to the arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted to swing the finger of the arm so as to free the tooth 100
10. 5. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projecting from the underside of its threaded end; of an insulating post rotatable within the tubular casing and projecting beyond one end thereof; a transmitting wire embedded in the insulating post, said transmitting wire being of greater length than the insulating post so as to extend beyond the ends of said insulating post; a plurality of 105 sparking points provided upon the end of the transmitting wire at the threaded end of the tubular casing; means provided upon the opposite end of the transmitting wire and adapted to connect said wire to a storage battery; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to engage one of the notches of the ratchet; a spring having one end held to the arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted to swing the finger of the arm so as to free the tooth 110
15. 5. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projecting from the underside of its threaded end; of an insulating post rotatable within the tubular casing and projecting beyond one end thereof; a transmitting wire embedded in the insulating post, said transmitting wire being of greater length than the insulating post so as to extend beyond the ends of said insulating post; a plurality of 115 sparking points provided upon the end of the transmitting wire at the threaded end of the tubular casing; means provided upon the opposite end of the transmitting wire and adapted to connect said wire to a storage battery; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to engage one of the notches of the ratchet; a spring having one end held to the arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted to swing the finger of the arm so as to free the tooth 120
20. 5. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projecting from the underside of its threaded end; of an insulating post rotatable within the tubular casing and projecting beyond one end thereof; a transmitting wire embedded in the insulating post, said transmitting wire being of greater length than the insulating post so as to extend beyond the ends of said insulating post; a plurality of 125 sparking points provided upon the end of the transmitting wire at the threaded end of the tubular casing; means provided upon the opposite end of the transmitting wire and adapted to connect said wire to a storage battery; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to engage one of the notches of the ratchet; a spring having one end held to the arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted to swing the finger of the arm so as to free the tooth 130

of said arm from engagement with the notch of the ratchet whereby said ratchet may be moved to rotate the insulating post for revolving the transmitting wire so as to register one of the sparking points of the transmitting wire with the sparking point of said tubular casing.

7. In a spark plug; the combination with a tubular casing having one end thereof exteriorly threaded and having its opposite end exteriorly reduced so as to provide an annular shoulder, said tubular casing having an annular band formed interiorly of its threaded end and having a sparking point projection from the underside of its threaded end; of an inner jacket rotatable within the tubular casing and having an annular band formed exteriorly at one end thereof and abutting against the annular band of the tubular casing whereby a concentric recess is provided between said inner jacket and the interior surface of the tubular casing; an insulating post held within the tubular casing and projecting beyond one end thereof; a transmitting wire embedded in the insulating post, said transmitting wire being of greater length than the insulating post so as to extend beyond the ends of said insulating post; a plurality of 30 sparking points provided upon the end of the transmitting wire at the threaded end of the tubular casing; means provided upon the opposite end of the transmitting wire and adapted to connect said wire to a storage battery; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring 40 provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to also engage one of the notches of the ratchet; a spring having one end held to the 45 arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted when moved to swing the finger of the arm so as to free the tooth of said arm from engagement with the notch of the ratchet; and a lever having one of its ends pivoted to the movable plate adjacent to the dog, said lever having a toe formed upon the edge of the pivoted end thereof and adapted when moved to swing the finger of the arm so as to free the tooth of said arm from engagement with the notch of the ratchet whereby said ratchet may be moved to ro-

tate the insulating post for revolving the transmitting wire so as to register one of the sparking points of the transmitting wire with the sparking point of said tubular casing; and a spiral spring encircling the 70 jacket of the insulating post and normally serving to retain said jacket and the insulating post within the tubular casing against displacement by suction created by the movement of the piston of a combustion engine.

8. In a spark plug; the combination with a tubular casing having one end thereof exteriorly threaded and having its opposite end exteriorly reduced so as to provide an 80 annular shoulder, said tubular casing having a sparking point projection from the underside of its threaded end; of an insulating post rotatable within the tubular casing and projecting beyond one end thereof; a transmitting wire embedded in the insulating post, said transmitting wire being of greater length than the insulating post so as to extend beyond the ends of said insulating post; a plurality of 85 sparking points provided upon the end of the transmitting wire at the threaded end of the tubular casing; a plate rigidly held upon the reduced end of the tubular casing; a ratchet provided upon the insulating post and having a plurality of 90 notches provided in the peripheral edge thereof; a plate movably held upon the insulating post between the notched ratchet and the rigidly held plate of the tubular casing; a dog pivoted upon the movable plate 100 and adapted to engage one of the notches of the ratchet; a spring provided upon the dog and normally serving to force said dog into engagement with one of the notches of the ratchet; an arm having one end pivoted upon the rigidly held plate; a finger formed upon the opposite end of the arm; a tooth formed upon one edge of the arm and adapted to also engage one of the notches of the ratchet; a spring having one end held to the 110 arm and having the other end thereof held to the rigidly held plate, said spring normally serving to force the tooth of the arm into engagement with one of the notches of the ratchet; and a lever having one of its ends pivoted to the movable plate adjacent to the dog, said lever having a toe formed upon the edge of the pivoted end thereof and adapted when manually moved to swing the finger of the arm so as to free the tooth of 115 said arm from engagement with the notch of the ratchet whereby said ratchet may be moved to rotate the insulating post for revolving the transmitting wire so as to register one of the sparking points of the transmitting wire with the sparking point of said tubular casing.

9. In a spark plug; the combination with a tubular casing having one end thereof exteriorly threaded and having its opposite 130

end exteriorly reduced so as to provide an annular shoulder, said tubular casing having a sparking point projection from the under-side of its threaded end; of an insulating post rotatable within the tubular casing and projecting beyond one end thereof; a transmitting wire embedded in the insulating post, said transmitting wire being of greater length than the insulating post so as to extend beyond the ends of said insulating post; a plurality of sparking points provided upon the end of the transmitting wire at the threaded end of the tubular casing; a plate rigidly held upon the reduced end of the tubular casing; a ratchet provided upon the insulating post and having a plurality of notches provided in the peripheral edge thereof; a plate movably held upon the insulating post between the notched ratchet and the rigidly held plate of the tubular casing; a dog pivoted upon the movable plate and adapted to engage one of the notches of the ratchet; a spring provided upon the dog and normally serving to force said dog into engagement with one of the notches of the ratchet; a pawl having one end pivoted upon the rigidly held plate; a finger formed upon the opposite end of the pawl; a tooth formed upon one edge of the pawl and adapted to also engage one of the notches of the ratchet; a spring having one end held to the pawl and having the other end thereof held to the rigidly held plate, said spring normally serving to force the tooth of the pawl into engagement with one of the notches of the ratchet; a handle having one of its ends pivoted to the movable plate adjacent to the dog, said handle having a toe formed upon the edge of the pivoted end thereof and adapted when manually moved to swing the finger of the pawl so as to free the tooth of said pawl from engagement with the notch of the ratchet whereby said ratchet may be moved to rotate the insulating post for revolving the transmitting wire so as to register one of the sparking points of the transmitting wire with the sparking point of said tubular casing; and a spring arranged around the insulating post and normally serving to retain said insulating post within the tubular casing against displacement by suction created by the movement of the piston of a combustion engine.

This specification signed and witnessed this ninth day of March A. D. 1911.
